BURIAL CASKET

Charles W. Glassner, Akron, Ohio

Application April 30, 1948, Serial No. 24,181

1 Claim. (Cl. 27—2)

1

It is an object of the invention to provide a casket which is sealed against entry of water by means of trapped air. A further object is to provide a casket which combines the functions of a conventional casket with those of outer burial boxes or shipping boxes and thus eliminates the need for such extra items. Still another object is to provide a casket, the major portion of which comprises an air-proof bell and a separate couch member as a bottom, adapted to be placed on the bell with the latter serving as a stand. Still another object is to attain the foregoing while maintaining the familiar form and appearance of a death lay-out.

To these and other ends will be made manifest hereinafter, the invention comprises certain novel and useful features, one embodiment of which is set forth in the accompanying specification and illustrated in the several views of the drawings, in which:

Fig. 1 is an exploded view in side elevation, with the two main parts in the relative position they occupy for interment or shipment;

Fig. 2 is a similar view with the bottom or couch member resting on the upper or bell member;

Fig. 3 is a section taken on the line 3—3 of Fig. 1; and

Fig. 4 is an enlarged detail of Fig. 3.

Referring to the drawings, there is shown generally at 1 a bell member which in proportions and general outline resembles the usual entire casket member. This bell member is open at the bottom and rests on a base member 2 near or at the marginal edges thereof. Functionally, therefore, the bell is the cover for the casket and the base corresponds to the casket proper, the overall appearance being not sensibly different from that of a conventional top-cover casket.

The base 2 forms a support for the couch member and will preferably comprise an enclosure formed from upstanding walls 3, which may take any suitable form consistent with the inclusion of a pallet 4 of the required size.

Carried on the underside of the base frame 5 is a continuous strip 6 of suitable gasket material, such as rubber, adapted to contact the base member 2 and form an air-seal and water-seal therewith due to the weight of the bell and auxiliary pressure and locking appendages. Of the latter, one type is for permanent sealing and locking, and one is temporary.

For temporary locking, aligned holes in the base 2 and base frame 5 will be engaged by bolts 7, and for permanent closure a self-locking fea-

2

ture is provided. In one form this may comprise notched heads 8 threadedly adjustable in the bell base 5, receivable in wells 9 having a spring-pressed pawl 10. As shown, these wells are provided in extensions 11 on the couch walls 3. Four of these are shown, but more may be employed if deemed necessary or desirable. For final closure, the bell is merely lowered so that the notched heads are received in the wells and the locking action effected by an added pressure to the necessary degree. Upon interment the weight of the earth will further increase the tightness of the seal.

For the purpose of placing the remains on view, the bell member is employed as a support. Saddle members 12 having a flat top and an underside shaped to conform to the profile of the top of the bell are placed on the bell and receive the base 2 with the pallet 4 and other appurtenances. In this arrangement, a back 13 is employed. This is a removable and reusable adjunct and is held in position as by depending legs 14 insertable in brackets 15 carried by the rear couch wall. The back affords the familiar appearance of the open cover of a casket. These backs may comprise various rear shapes and styles selectable to suit any occasion, and may be further varied in appearance and given added durability by the use of slip covers.

Of the several useful aspects of the present invention, the one most immediately apparent and appreciated is the fact that the casket, per se, is adequate for shipment or interment without extra closures. This minimizes expense, and, perhaps more importantly, saves space. Not only is space saved as a matter of financial economy, but the effect is to bring about narrower limits of standardization of the various activities incident to burials. In the past, not only has the size of the deceased been a consideration; the ultimate factor has been the size of the outer container, which has been subject to wide variation and determined by whim or fancy. The casket of this invention, being rugged and air-sealed, serves as the ultimate repository, and needs only a minor covering such as a cloth drape in shipping or burial for masking purposes.

A second important consideration is the air-seal and its location. The bell member being structurally continuous and imperforate is air-impermeable in every sense, and the only region subject to deterioration and ultimately vulnerable to air is the gasketed line of closure at the bottom. The most undesirable consequence of interment is the access of ground water into the

interior of a casket. In general, water will attain the level of the seal exteriorly of the casket before decay of the seal. But whether before or after such decay, the continuous and imperforate nature of the bell will ensure that seepage of water into the interior will be avoided due to the air lock. The situation may be likened to that obtaining in the case of a diving bell. In fact this function is so pronounced that prevention of water ingress will be attained even without the gasket seal. An air lock is not attainable where the seal is at or near the top.

While presenting the foregoing advantages, the casket of this invention lends itself readily to an arrangement for viewing of the remains which, in effect, is in no way a departure from or inferior to the appearance of the customary layout, and is attended with desirable economies.

For shipping purposes it may be desirable to provide means of securement for the remains, and to this end I provide additional brackets such as 15 on the opposite couch wall for the accommodation of straps 16.

Considering the novel features of this invention relative to dispensing with the need for outer containers, it will be desirable that certain forms of reenforcement be employed interiorly of the bell member. As shown at 17 I have provided rib members for the underside of the top dome of the bell as being the most vulnerable region in shipping, and particularly under the weight of filled earth. Such reenforcement has the additional advantage of enabling the use of lighter gage of material in the bell while maintaining necessary strength and thus reducing costs. The proper location and form of reenforcement will suggest themselves as regards particular cases that may arise, the general thought here involved being the provision of reenforcement as an adjunct to a casket which combines the functions of an outer container.

While certain shapes, forms and mechanical devices have been shown, it will be understood that the invention is not intended to be limited thereby. For example, the gasket means may be located other than on the bell, for instance on the base. The particular locking means shown are subject to variation, as is the manner of mounting the back. The bell and base may be 50 of any suitable air-proof material, such as steel,

copper, ceramic or plastic materials, for instance. Preferably, the permanent lock will be located inwardly of the seal so as to avoid corrosive associations.

5 The embodiment of the invention described herein is for illustrative purposes and is not to be deemed as limited except as shall appear from the spirit and scope of the appended claim.

10 Where the word "substantial" is used in the claim, it is intended to qualify to the extent of serving the objects set forth in this specification. In particular regard to the size of the bell, this will have reference to the level above which rise of ground water is not desired.

15 What is claimed is:

A burial casket comprising a top closure of continuous and imperforate structure having dependent sides forming substantially the entire vertical extent of the casket, a separate, low base member upon which the top closure is received in closing relation, a couch member on the base member, and means along each side of the couch member for attachment of straps to secure an object on the couch member, said 25 means comprising upright panels with brackets having vertically arranged openings, thereby serving alternately for support of an upright background panel lengthwise of the couch member.
